US0D1105848S

(12) **United States Design Patent** (10) **Patent No.:** **US D1,105,848 S**
(45) **Date of Patent:** **** Dec. 16, 2025**

(54) **BEVERAGE WARMER**

(71) Applicant: **Nextboom, Inc.**, Boulder, CO (US)

(72) Inventor: **J. Michael Wolfe**, Boulder, CO (US)

(73) Assignee: **Nextboom, Inc.**, Boulder, CO (US)

(**) Term: **15 Years**

(21) Appl. No.: **29/885,093**

(22) Filed: **Feb. 20, 2023**

Related U.S. Application Data

(62) Division of application No. 29/837,596, filed on May 6, 2022, now Pat. No. Des. 981,163.

(51) **LOC (15) Cl.** **07-01**

(52) **U.S. Cl.**

USPC **D7/323; D7/536**

(58) **Field of Classification Search**

USPC D7/323, 361, 394, 402, 507, 509–511,
D7/514, 515, 519–521, 533–536, 900

(57) **CLAIM**

The ornamental design for a beverage warmer as shown and described.

DESCRIPTION

FIG. 1 is a front-side top perspective view of a beverage warmer;

FIG. 2 is a front view of the beverage warmer of FIG. 1;
FIG. 3 is a rear view of the beverage warmer of FIG. 1;
FIG. 4 is a left view of the beverage warmer of FIG. 1;
FIG. 5 is a right side view of the beverage warmer of FIG. 1;

FIG. 6 is a top view of the beverage warmer of FIG. 1; and,
FIG. 7 is a bottom view of the beverage warmer of FIG. 1.
The broken lines in the drawings illustrate portions of the
beverage warmer that form no part of the claimed design.

1 Claim, 7 Drawing Sheets

US D1,105,848 S
